TURBINE

Frank Romex Viera, Glendora, Calif.

Application February 22, 1943, Serial No. 476,747

4 Claims. (Cl. 253—165)

The present invention relates to new and useful improvements in turbines, and has for one of its important objects to provide, in a manner as hereinafter set forth, a device of this character comprising a novel construction, combination and arrangement whereby centrifugal as well as kinetic force is utilized to assist the impelling fluid in actuating the driven member.

Another important object of the invention is to provide, in a turbine of the character described comprising a hollow, cylindrical fluid-actuated rotor, unique means for regulating or controlling the speed of said rotor.

Still another important object of the invention is to provide a fluid turbine of the aforementioned character which embodies novel means for rotatably supporting and lubricating the shaft of the rotor.

Other objects of the invention are to provide a fluid turbine of the character described which will be comparatively simple in construction, strong, durable, highly efficient and reliable in use, quiet, compact, of light weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in longitudinal section through a turbine constructed in accordance with the present invention.

Figure 2 is a cross sectional view, taken substantially on the line 2—2 of Figure 1.

Figure 3 is a cross sectional view, taken substantially on the line 3—3 of Figure 1.

Figure 4 is a view in longitudinal section through the fluid strainer or filter, taken substantially on the line 4—4 of Figure 1.

Figure 5 is a view in vertical section through another form of the invention.

Figure 6 is a view in horizontal section, taken substantially on the line 6—6 of Figure 5.

Figure 7 is an elevational view of the rotor.

Figure 8 is a detail view in perspective of the speed regulating member.

Referring now to the drawings in detail, it will be seen that reference numeral 1 designates generally an elongated casing of suitable dimensions and material, said casing comprising a base portion 2. Communicating with the casing 1 at one end thereof is a longitudinally extending fluid outlet 3.

The end portions of the casing 1 are provided with oil chambers 4. Plates 5 close the chambers 4. Filling plugs 6 are provided for the oil chambers 4. The chambers 4 are also provided with drain plugs 7.

Transverse partitions 8 are provided in the upper portions of the oil chambers 4. Suitable bearings 9 are provided in the partitions 8. A longitudinal shaft 10 is journaled in the bearings 9. Oil pick-up rings 11 are mounted on the shaft 10 outwardly of the bearings 9. Oil throw-out disks 12 are provided on the shaft 10 inwardly of the bearings 9. Suitable seals 13 prevent leakage from the chambers 4 around the shaft 10.

Fixed on the shaft 10 is a sleeve 14. The sleeve 14 carries a hollow cylindrical rotor 15 comprising a closed end 16, the other end of said rotor being open. A removable speed change ring 17 is threaded on the open end of the rotor 15. Fluid throw-off disks 18 are provided adjacent the ends of the rotor 15.

Manifolds 20 extend longitudinally into the rotor 15 through the open end thereof. The manifolds 20 are provided with any suitable number of nozzles 21. The manifolds 20 may be connected with any suitable source of fluid. Strainers or filters 22 are provided for preventing foreign matter from entering the manifolds 20 and clogging the nozzles 21. As illustrated to advantage in Figure 2 of the drawings, the nozzles 21 of the manifolds 20 are arranged to drive the rotor 15 in opposite directions.

It is thought that the operation of the turbine will be readily apparent from a consideration of the foregoing. Briefly, jets of the impelling fluid are directed tangentially against the inner periphery of the cylindrical rotor 15 by the nozzles 21 on either of the manifolds 20. Any suitable means may be provided for controlling the manifolds 20. The tangential jets of fluid under pressure impinging the inner periphery of the rotor 15 frictionally drive said rotor. The fluid flows from the open end of the rotor 15 and escapes to any suitable point of discharge through the outlet 3 in the casing 1. As the rotor 15 gathers speed, the frictional contact therewith of the fluid therein is increased by centrifugal force. Thus, a film of the fluid is caused to adhere to the rotor. The thickness of this film and consequently the speed of the rotor 15 is changed by the application of different removable rings 17 having openings of different sizes. As the thickness of the fluid film increases, the speed of the rotor 15 decreases.

The modification which has been illustrated in Fig. 5 comprises a vertically elongated casing 23 including an enlarged base portion 24. A fluid outlet 25 communicates with the lower portion 24 of the casing 23.

Journalized in suitable bearings 26 which are provided therefor in the upper and lower portions of the casing 23 is a vertical shaft 27. Oil chambers 28 are provided for lubricating the bearings 26. Filling and drain plugs 29 and 30, respectively, are provided for the oil chambers 28. Suitable seals 31 prevent oil leakage from the chambers 28 past the shaft 27.

A sleeve 32 is fixed on the shaft 27. The sleeve 32 carries a hollow cylindrical rotor 33 having a closed upper end 34, the lower end of said rotor being open. A speed change ring 35 is removably mounted on the open lower end of the vertical rotor 33. Extending upwardly into the rotor 33 from the lower end thereof is a pair of manifolds 36 comprising suitable nozzles 37. The manifolds 36 are connected to any suitable source of impelling fluid. Strainers or filters 38 are provided for the manifolds 36. Fluid throw-off disks 39 are provided on the shaft 27 above and below the rotor 33.

In construction and operation, the members 21 to 39, inclusive, are substantially similar to the corresponding members of the embodiment of Figure 1. Jets of fluid under pressure from either of the manifolds 36 impinge the inner periphery of the hollow cylindrical rotor 33 and actuate same, said jets being directed tangentially against said rotor. The spent fluid flows downwardly into the enlarged lower portion 24 of the casing 23 through the open end of the rotor 33 and is discharged through the outlet 25.

It is believed that the many advantages of a turbine constructed in accordance with the present invention will be readily understood, and although preferred embodiments of the device are as illustrated and described, it is to be understood that further modifications and changes in the details of construction may be resorted to which will fall within the scope of the invention as claimed.

What is claimed is:

1. A turbine of the character described comprising a casing, a hollow, cylindrical rotor journalized in said casing, said rotor being closed at one end and open at its other end, means for discharging jets of fluid against the inner periphery of the rotor for actuating same, and means on the open end of the rotor for causing the fluid to assume a film of pre-determined thickness on the inner periphery of the rotor, the last-named means including a ring threaded on said open end of the rotor and having an annular flange projecting inwardly beyond the inner periphery of the latter, said ring being removable to permit selective use of rings having flanges of different widths so that the speed of the rotor may be changed.

2. A turbine of the character described comprising an elongated casing, aligned bearings in opposite ends of said casing, a shaft journalized in the bearings, a sleeve fixed on said shaft between the bearings, a hollow, elongated cylindrical rotor fixed on said sleeve within the casing, said rotor being closed at one end and open at its other end, a manifold, for connection with a source of fluid under pressure, extending longitudinally into the rotor through the open end thereof, nozzles on the manifold for directing a series of jets of the fluid against the inner periphery of the rotor at different points along the length thereof for actuating said rotor, and a removable ring mounted on the open end of the rotor and having an annular flange extending inwardly beyond the inner periphery of the latter to cause the fluid to assume a film of pre-determined thickness on the inner periphery of the rotor, said ring being removable to permit selective use of rings having flanges of different widths so that the speed of the rotor may be changed.

3. A turbine of the character described comprising a horizontally elongated casing, oil chambers in the end portions of said casing, transverse partitions in the chambers, bearings in said partitions, a longitudinal shaft journalized in the bearings, oil pick-up rings on the shaft in the chambers, a sleeve fixed on the shaft, a hollow, cylindrical rotor fixed on said sleeve, said rotor being closed at one end and open at its other end, a manifold, for connection with a source of impelling fluid, extending longitudinally into the rotor through the open end thereof, nozzles on the manifold for directing jets of the fluid tangentially against the inner periphery of the rotor, and a removable ring threadedly mounted on the open end of the rotor and extending inwardly beyond the inner periphery thereof for causing the fluid to assume a film of pre-determined thickness on the inner periphery of the rotor.

4. A turbine of the character described comprising a vertically elongated casing, aligned bearings in the upper and lower portions of said casing, a vertical shaft journalized in said bearings, a sleeve fixed on the shaft, a rotor fixed on said sleeve, said rotor being closed at its upper end and open at its lower end, a manifold, for connection with a source of impelling fluid, extending upwardly in the rotor through the lower end thereof, nozzles on the manifold for directing jets of the fluid tangentially against the inner periphery of the rotor for actuating same, and a removable ring threadedly mounted on the lower end of the rotor and extending inwardly beyond the inner periphery thereof for causing the fluid to assume a film of pre-determined thickness on the inner periphery of the rotor.

FRANK ROMEX VIERA.
